CLAIM

The ornamental design for an erectile band, as shown and described.

DESCRIPTION

FIG. 1 is a top, front, right perspective view of a first erectile band, showing our new design;
 FIG. 2 is a front elevational view thereof;
 FIG. 3 is a back elevational view thereof;
 FIG. 4 is a right side elevational view thereof;
 FIG. 5 is a left side elevational view thereof;
 FIG. 6 is a top plan view thereof;
 FIG. 7 is a bottom plan view thereof;
 FIG. 8 is a top, front, right perspective view of a first alternative embodiment of the first erectile band, showing our new design;
 FIG. 9 is a front elevational view thereof;
 FIG. 10 is a back elevational view thereof;
 FIG. 11 is a right side elevational view thereof;
 FIG. 12 is a left side elevational view thereof;
 FIG. 13 is a top plan view thereof;
 FIG. 14 is a bottom plan view thereof;
 FIG. 15 is a top, front, right perspective view of a second alternative embodiment of the first erectile band, showing our new design;
 FIG. 16 is a front elevational view thereof;
 FIG. 17 is a back elevational view thereof;
 FIG. 18 is a right side elevational view thereof;
 FIG. 19 is a left side elevational view thereof;

FIG. 20 is a top plan view thereof;
 FIG. 21 is a bottom plan view thereof;
 FIG. 22 is a top, front, right perspective view of a third alternative embodiment of the first erectile band, showing our new design;
 FIG. 23 is a front elevational view thereof;
 FIG. 24 is a back elevational view thereof;
 FIG. 25 is a right side elevational view thereof;
 FIG. 26 is a left side elevational view thereof;
 FIG. 27 is a top plan view thereof;
 FIG. 28 is a bottom plan view thereof;
 FIG. 29 is a top, front, right perspective view of a second erectile band, showing our new design;
 FIG. 30 is a front elevational view thereof;
 FIG. 31 is a back elevational view thereof;
 FIG. 32 is a right side elevational view thereof;
 FIG. 33 is a left side elevational view thereof;
 FIG. 34 is a top plan view thereof;
 FIG. 35 is a bottom plan view thereof;
 FIG. 36 is a top, front, right perspective view of a first alternative embodiment of the second erectile band, showing our new design;
 FIG. 37 is a front elevational view thereof;
 FIG. 38 is a back elevational view thereof;
 FIG. 39 is a right side elevational view thereof;
 FIG. 40 is a left side elevational view thereof;
 FIG. 41 is a top plan view thereof;
 FIG. 42 is a bottom plan view thereof;
 FIG. 43 is a top, front, right perspective view of a second alternative embodiment of the second erectile band, showing our new design;
 FIG. 44 is a front elevational view thereof;
 FIG. 45 is a back elevational view thereof;
 FIG. 46 is a right side elevational view thereof;
 FIG. 47 is a left side elevational view thereof;
 FIG. 48 is a top plan view thereof;
 FIG. 49 is a bottom plan view thereof;
 FIG. 50 is a top, front, right perspective view of a third alternative embodiment of the second erectile band, showing our new design;
 FIG. 51 is a front elevational view thereof;
 FIG. 52 is a back elevational view thereof;
 FIG. 53 is a right side elevational view thereof;
 FIG. 54 is a left side elevational view thereof;
 FIG. 55 is a top plan view thereof;
 FIG. 56 is a bottom plan view thereof;
 FIG. 57 is a top, front, right perspective view of a third erectile band, showing our new design;
 FIG. 58 is a front elevational view thereof;
 FIG. 59 is a back elevational view thereof;
 FIG. 60 is a right side elevational view thereof;
 FIG. 61 is a left side elevational view thereof;
 FIG. 62 is a top plan view thereof;
 FIG. 63 is a bottom plan view thereof;
 FIG. 64 is a top, front, right perspective view of a first alternative embodiment of the third erectile band, showing our new design;
 FIG. 65 is a front elevational view thereof;
 FIG. 66 is a back elevational view thereof;
 FIG. 67 is a right side elevational view thereof;
 FIG. 68 is a left side elevational view thereof;
 FIG. 69 is a top plan view thereof; and,
 FIG. 70 is a bottom plan view thereof.

The dash-dot broken lines in the drawings are for the purpose of illustrating a boundary line which form no part of the claimed design.
